UNITED STATES PATENT OFFICE.

THOMAS MUNRO, OF PHILADELPHIA, PENNSYLVANIA.

VEHICLE SPRING COVER.

Application filed April 13, 1925. Serial No. 22,530.

My invention relates more especially to covers used on the springs of automobiles for the purpose of preventing dust, dirt and water from entering between the leaves and for supplying lubricant in such manner as to constantly lubricate the relatively movable surfaces of the leaves. Such covers as hitherto constructed have generally comprised an outer layer or envelop of flexible waterproof material lined with felt or other suitable absorbent material and of such size as to lie over the top leaf of the spring and extend down adjacent the sides of the leaves to a point slightly below the bottom leaf where the free edges of the cover are secured together in any suitable way so as to retain the cover on the spring and hold it closely adjacent thereto.

In automobiles as at present constructed it is customary to provide the springs with a plurality of inverted U-shaped clips one or more of which is disposed about each spring with its free ends projecting for a relatively considerable distance above the top leaf so as to enable the clip to be secured in position on the spring by a bolt or rivet extended transversely through said ends above the plane of the top leaf, the function of these clips being to prevent the separation of the spring leaves upon the rebound of the spring. It is therefore impossible when attaching to the spring a spring cover of the usual type to cause the cover to lie flat along the top leaf since the said projecting ends of the clips force the cover away from the leaves both directly in their vicinity and also for a considerable distance on each side of each clip. This causes a very unsightly hump or bunch on the exterior of the cover adjacent each clip and, in addition, has a tendency to correspondingly raise the free edges of the cover so that the latter, instead of smoothly following the contour of the lower surface of the spring in generally parallel relation therewith, are pulled or curved up for a considerable distance adjacent each clip; thus instead of depending below they are frequently above the plane of the bottom of the spring adjacent the clips which materially interferes with the proper attachment of the means by which said free edges of the cover are secured together after the latter is placed over the spring. In short, the projecting ends of the clips prevent the convenient and proper attachment of the cover about the spring, interfere with its neat appearance

when in position and finally, through the relative movement of the spring and cover under operative conditions, wear through both the lining and the envelop of the latter at their points of contact therewith and thereby render the cover more or less unserviceable after a relatively short period of use.

It is therefore an object of the present invention to provide a spring cover so constructed as to embody pockets or recesses for the reception of the ends of the spring clips which project above the plane of the upper surface of the top leaf of the spring.

A further object of the invention is to provide a spring cover having pockets or recesses for the reception of the projecting ends of the spring clips formed integral with the exterior portion or envelop of the cover and so arranged that when the cover is in operative position on the spring the ends of the clips will be received in said pockets without any undue strain being placed on the side or other portions of the cover in the vicinity of the clips, whereby the free longitudinal edges of the cover can assume their proper position substantially parallel with the bottom of the spring.

Still further objects of my invention are to relieve the spring cover, by the provision of suitable pockets or recesses for the reception of the projecting ends of the spring clips, from excessive wear in the vicinity of said projecting ends; to facilitate the operation of attaching the cover to the spring and to enhance its appearance thereon by preventing bunching up of the cover in the vicinity of the clips.

My invention further includes other objects and novel features of construction and arrangement hereinafter more particularly referred to or which will be apparent from the accompanying drawing taken in connection with the following description of a preferred embodiment of the invention as there- in illustrated.

In the said drawing Fig. 1 is a perspective view of a spring cover constructed in accordance with my invention as it appears in extended position before attachment to the spring; Fig. 2 is a transverse section on line 2—2 in Fig. 1; Fig. 3 is a longitudinal central section on line 3—3 in Fig. 1; Fig. 4 is a central longitudinal section of the spring cover in position upon a vehicle spring which is shown in side elevation and Fig. 5 is a side elevation of the cover in position on the

spring. The same symbols are used to designate similar parts in the several figures.

In the particular embodiment illustrated, the cover comprises an outer sheet or layer, which I conveniently term the envelop, of flexible, preferably waterproof and oilproof fabric such as pantasote, imitation leather or even real leather in some instances. This envelop comprises a central portion 1 of sufficient width and length to overlie the top of the spring with which the cover is to be associated and marginal portions or flaps 2, 2 of sufficient width to be turned down over the sides of the spring and cover the same when the cover is in position thereon. Since automobile springs are ordinarily of decreasing vertical thickness from their centers toward their outer ends, the longitudinal edges 3, 3 of the side flaps of the cover are preferably arranged to converge from the inner end 5 of the cover which is intended to lie most nearly adjacent the center of the spring to the opposite or outer end 6 so that when the flaps are turned down alongside of the spring the longitudinal edges 3, 3 will substantially follow the contour of the bottom of the spring.

The side flaps 2 of the cover may be lined with a lining 7, 7 formed of a sheet of suitable absorbent material such as felt or the like which is capable of absorbing oil, these linings respectively extending from adjacent the marginal edges of the side flaps to approximately the side edges 8, 8 of the central portion 1 of the cover, the side marginal extremities of the envelop being turned over as at 9, 9 so as to cover the adjacent edges of the linings and the several layers then stitched together by stitches 10 extending entirely around the edges of the cover. Preferably a longitudinally extending stiffening wire 11 is disposed in the turned over edge of the envelop adjacent the outer edge of the felt liner for the purpose of preventing endwise buckling of the cover when in operative position on the spring, and a plurality of eyelets may be disposed adjacent the lateral edges of the cover for engagement by the attaching means by which the cover is secured on the spring.

For the purpose of receiving the upwardly projecting ends C' of the spring clips C which, as hitherto stated, are disposed at intervals on automobile springs as now customarily constructed, I provide the central portion of the envelop at suitably spaced points with recesses or pockets 13, 13' formed by striking up the material of the envelop during the manufacture of the latter by means of a suitable die or other tool so that that part of the material which forms the pocket is forced out of the general plane of the envelop and caused to assume substantially arcuate form, when viewed in longitudinal section as in Fig. 3 rising above the plane of the top of the envelop and intersect-

ing the latter in transversely extending lines 15, the transverse width of the pocket thus formed being preferably slightly greater than the width of the central portion 1 of the cover so that the pocket will overlie and readily receive the spring clip which is, of course, of somewhat greater width than the width of the spring leaves. The sides 16 of the pocket which extend substantially vertically are also formed simultaneously with the top of the pocket just described and in the same operation, and it has been found in practice that by the use of a suitable die it is possible to strike up these pockets without excessively stretching the material of the envelop and without causing creases or abrasions in the latter in the vicinity of the pockets so that the upper surface of the envelop, as well as the pockets themselves, is entirely smooth, in consequence of which the completed cover presents a very neat and attractive appearance. It will of course be understood that the vertical height or depth of the pockets is sufficient to receive the projecting ends of the spring clips without causing the latter to bear with excessive pressure on the interior of the cover when the latter is fitted on the spring, and further, that the number of pockets provided in each cover and their relative longitudinal spacing will be determined by the number of spring clips and their longitudinal spacing upon the spring of the particular automobile or other vehicle with which the cover is designed to be used; thus, where the makers of a particular car provide it with springs having three clips between the outer end and the center, the cover designed for that car will be provided with a corresponding number of pockets properly longitudinally spaced to accommodate the clips therein, while a cover intended for use on another car having but two or even one clip on each of its springs between the ends and center thereof would preferably be provided with a corresponding number of properly spaced pockets.

For the purpose of receiving and distributing the oil or other lubricant injected into the interior of the cover from time to time under operative conditions, the cover is provided with a longitudinally extending strip 17 of felt or other lubricant absorbing material of substantially the width of the central part 1 of the envelop and arranged to extend therebeneath from one end of the cover to the other. As clearly shown in Figs. 3 and 4 this strip 17 is carried up into the interior of each of the pockets 13 so as to lie therein adjacent the inner surface of the envelop, but between the pockets the strip is preferably spaced from the under side of the cover by spacer strips 18 of like material and of similar width to the strip 17. These spacer strips ordinarily are, however, of different lengths, each strip being preferably adapted to extend

substantially for the space or length defined by the superjacent flat portion of the envelop; the length of each spacer strip will therefore generally be determined by the size and relative disposition of the pockets 13. Thus, in the particular cover illustrated, the spacer strip 18 extending from the edge 5 substantially to the adjacent end of the pocket 13 is somewhat shorter than the strip 18' which is disposed between the two pockets, while the strip 18'' disposed between the edge 6 and the pocket 13' is very much shorter than either of the others. The strip 17 as well as the spacer strips are permanently secured to the envelop in any suitable way, conveniently by the use of longitudinally spaced split rivets 20 arranged along the center line of the cover and extending through the several parts.

To enable the introduction of oil or other lubricant to the interior of the cover when positioned on the spring, a hole is punched through the envelop at any convenient point and preferably on the center line thereof and surrounded and reinforced by an eyelet 21 provided with a removable cap 22 in such manner that when the latter is detached from the eyelet oil may be injected through the latter upon the subjacent spacer strip from which point the oil finds its way to the strip 17 and travels therealong in both directions so as to saturate the entire strip as well as the other spacer strips and also works out on the linings 7, 7 so as to saturate them. As under operative conditions these linings are constantly maintained against the sides of the spring the oil with which they are saturated gradually works between the spring leaves by capillary attraction so as to adequately lubricate the contacting and relatively movable faces of the leaves.

A spring cover constructed substantially as hereinbefore described may be operatively attached to a spring S by first placing the cover thereon with its central portion 1 aligned with the top leaf of the spring and the under side of the strip 17 in contact therewith. The side portions or flaps of the cover are then turned vertically down adjacent the sides of the spring and the free longitudinal edges 3, 3 secured together by any suitable means extending between said edges beneath the spring, and while said means may partake of various forms I prefer to employ for that purpose the means disclosed and claimed in U. S. Patent No. 1,667,735, granted to me on May 1, 1928, to which reference may be had for a further description thereof. It will be apparent that when so positioned on the spring the portions of the envelop between the pockets and also between the ends of the pockets and the ends of the cover will be raised for a relatively considerable distance above the top leaf S' by the interposition of the strips 17 and spacer strips between the envelop and the leaf and that the upwardly projecting ex-

tremities C' of the spring clips C will be received in the pockets of the cover and rest therein without causing any stretching or undue distortion of the adjacent portions of the latter; thus the longitudinal edges 3, 3' of the latter are not pulled up adjacent each clip but smoothly follow the general contour of the under surface of the spring throughout its entire length enabling the proper attachment and functioning of the means by which the cover is secured in position on the spring and keeping all parts of the sides of the spring properly covered. It will further be observed by reference to Fig. 4 that as the vertical height or depth of the pockets is sufficient to readily receive the projecting ends of the clips without the necessity of downwardly straining the adjacent portions of the cover, the wear on the cover at its points of contact with the ends of the clips is not materially greater than the wear at any other point, in consequence of which the ends of the clips do not work through the cover under the relative movement between the parts induced by the constant flexing of the spring under operative conditions. This wearing of the cover by the spring clips is of constant occurrence with covers as hitherto constructed and frequently serves to render such covers more or less unserviceable after a relatively short period of use.

As the pockets in my improved spring cover are formed integral with the envelop and conveniently by a single operation, the cost of manufacture of the cover is not thereby unduly increased, and possibility of oil leakage in the vicinity of the pockets prevented, while the wearing qualities and appearance of the cover and its ability to properly hug the spring and permit the proper attachment and functioning of the attaching means, whatever may be their nature, is materially enhanced.

While I have herein described and illustrated with considerable particularity a preferred embodiment of my invention, I do not thereby desire or intend to specifically limit myself thereto as minor changes and modifications may be made in the design and construction of the cover and the size, number and disposition of the pockets varied as may be desired for the purpose of adapting the cover for use on different makes of automobiles and types of springs without departing from the spirit and scope of the invention as defined in the appended claims.

Having thus described my invention, I claim and desire to protect by Letters Patent of the United States:

1. A spring cover for vehicle springs comprising an outer envelop of flexible material having a central portion adapted to lie adjacent the top leaf of a spring and provided with a recess in its under face formed by striking up the material of the envelop and with side flaps laterally disposed with respect

to the central portion and adapted to be turned down adjacent the sides of the spring, a strip of absorbent material disposed beneath said central portion and extending 5 from one end of the cover to the other and into said recess to form a lining therefor, said strip being of less width than said recess, spacer strips of similar material interposed between said strip and the envelop adjacent 10 each end of the recess, and means for securing said envelop, spacer strips and strip together.

2. A spring cover for vehicle springs comprising an outer envelop of flexible material having a central portion adapted to extend 15 adjacent the top of a spring and side flaps laterally disposed with respect to said central portion adapted to lie adjacent the sides of the spring and a lining of absorbent material for each of said side flaps, said envelop

being provided with a recess in its under 20 face extending across said central portion and formed by striking up the material of the envelop, a strip of absorbent material of less width than said recess extending longitudinally beneath said central portion from 25 one end of the cover to the other and lining said recess, spacer strips of absorbent material interposed between the longitudinal strip and the envelop at each end of the recess, and means for securing said envelop, spacer 30 strips and longitudinal strip together, comprising a plurality of rivets disposed at spaced intervals and extending through all of said parts.

In witness whereof, I have hereunto set 35 my hand this 12th day of March, 1925.

THOMAS MUNRO.
